UNITED STATES PATENT OFFICE.

WILFRED J. ORMER, OF DAYTON, OHIO, ASSIGNOR TO THE RECORDING AND COMPUTING MACHINES COMPANY, OF DAYTON, OHIO, A CORPORATION OF OHIO.

OPERATING MECHANISM FOR FARE REGISTERS AND INDICATORS.

1,110,370.

Specification of Letters Patent.

Patented Sept. 8, 1914.

Application filed September 8, 1908. Serial No. 452,127.

To all whom it may concern:

Be it known that I, Wilfred J. Ormer, a citizen of the United States, residing at Dayton, in the county of Montgomery and State of Ohio, have invented certain new and useful Improvements in Operating Mechanism for Fare Registers and Indicators, of which the following is a specification, reference being had thereto to the accompanying drawings:

10 This invention relates to operating mechanism for fare registers and fare indicators, and is designed more particularly for use in connection with that type of street car known as the "pay as you enter" car, in which the conductor stands on the rear platform of the car and receives the fare from the passenger as he enters the car.

15 The object of the invention is to provide an operating mechanism of this character which can be controlled by the conductor from his position on the platform; to provide such a mechanism which can be actuated by the conductor to set the fare register and the fare indicator and then actuated by other means to register the fare; to provide selector mechanism by means of which the selector can set the fare register to register the particular fare received; to provide selector mechanism which may be controlled 20 by a single operator of a controlling member to provide means for locking the operating mechanism against movement until the fare register has been set; to provide an indicator which will be visible both to the passengers within the car and those on the platform and which will be actuated from the setting mechanism or selector; to provide a fare indicator which will be under the control of the conductor when in his position on the 25 platform and may be actuated by him to indicate the fare received; to provide such an indicator which may be actuated simultaneously with the setting of the fare register; and to provide an improved circuit breaker and closer for controlling the selector mechanism.

30 With these objects in view my invention consists in certain novel features and in certain combinations and arrangements of parts hereinafter to be described, and more particularly pointed out in the claims.

35 In the accompanying drawings, Figure 1 is an end elevation of a street car equipped with my invention, with the rear end of the

car broken away; Fig. 2 is a sectional view on the line $y-y$ of Fig. 1, showing a top plan view of the mechanism; Fig. 3 is a side elevation of the selector mechanism; Fig. 4 is a top plan view of the same; Fig. 5 is a transverse, sectional view of the fare indicator, showing the operating mechanism therefor in side elevation; Fig. 6 is a front elevation of the fare indicator and the operating mechanism therefor; Fig. 7 is a longitudinal sectional view of the circuit breaker and closer; Fig. 8 is transverse, sectional view of the circuit breaker and closer; Fig. 9 is a diagrammatic view of the circuits; Fig. 10 is a detail view of the central casting of the turnstile; Fig. 11 is a sectional view taken on the line $w-w$ of Fig. 10 and looking in the direction of the arrows; Fig. 12 is a horizontal, sectional view of the rear portion of a car, showing a modified form thereof; Fig. 13 is a top plan view of a fare register of one type to which my invention may be applied; Fig. 14 is a detail view of the setting and operating member for said register; Fig. 15 is an end elevation of a portion of such a register showing said operating member and its connecting devices in elevation; and Fig. 16 is a detail view of the clutch mechanism between the actuating shaft and the operating member.

40 In these drawings I have illustrated one embodiment of my invention and have shown the same as applied to a street car, 1, of the "pay as you enter" type. This car has an enlarged platform 2 and is provided with two doors, an entrance 3 and an exit 4 leading from the car proper to this platform. The platform itself is divided into two passageways by means of a railing 5 extending rearwardly from a point near the inner side of the entrance doorway to a point near the center of the platform, then laterally to the edge of the platform, thus forming an aisle, between the railing 5 and the rear end of the platform, which leads to the entrance. This aisle is preferably provided with a turnstile 6 to control the entrance of the passengers and cause them to pass close to the rail 5, behind which the conductor stands in the space between the two doors, thus enabling the conductor to collect the fares as the passengers enter the car.

45 In the form of mechanism herein shown,

I mount a fare register, which is indicated by the reference numeral 7, upon the inner side of the partition 8 which divides the car proper from the platform. This fare register may be of any suitable type which is adapted to register any one of a series of different fares and which has means for setting the register to register a particular fare and means for operating the registering mechanism to register that fare. I have more particularly designed the invention for use with and have here shown the same as applied to a fare register, such as is shown and described in Patent No. 15 848,262, granted March 26, 1907, to Ohmer, Whistler and McAllister. In the register of this patent a single actuating member is operatively connected to and forms a part of both the setting means and the operating 20 means. The means for setting the register to register a particular fare and for operating the same to register that fare form no part of the present invention and I have, therefore, shown only so much of these 25 means as is necessary to illustrate the application of my invention thereto. The phrase "setting the fare register" and similar expressions, as used in the specification and claims, refer to the operation of setting the several parts of the fare registering mechanism in such a position that, when the registering mechanism is operated, a predetermined fare will be registered. The actuating member of the fare register is 30 here shown at 9 and is adapted to be rotated about a longitudinal axis to set the fare register and to be moved longitudinally to operate the registering mechanism to register the fare. In Figs. 13 to 16 I have illustrated one form of register in which such an actuating member is employed. This register comprises end members 200 having journaled therein countershafts, one of which is indicated at 201. Mounted upon 35 each countershaft is a plurality of printing counters each preferably comprising a type disk 202 and a gear wheel 203. Extending parallel with this countershaft and in a plane located above the same is an actuator 40 shaft 204 having a suitable toothed actuator 205 slidably mounted thereon but rotatable therewith. This actuator is adapted to be moved longitudinally of the actuator shaft 204 to bring the same into operative relation 45 with the desired counters and then to be rotated, by the rotation of the shaft, to actuate said counters. The longitudinal movement of the actuator is accomplished by means of a setting shaft 206 which is here 50 shown as a screw shaft rotatably mounted in the end members and having mounted thereon a nut 207 provided with a depending portion or yoke 208, the arms of which extend on the opposite sides of the actuator 55 205, thereby causing the actuator to move with the nut as the latter moves along the screw shaft. The actuating member 9 is here shown in the form of a sleeve rotatably and slidably mounted in one of the frame members 200 and telescoping the end of the setting shaft 206. This sleeve is splined or otherwise connected to the shaft 206 so as to cause the latter to rotate therewith, thereby permitting the sleeve to reciprocate relatively to the shaft. The outer end of the actuating member is adapted to be connected with suitable operating devices as hereinafter described and the relation thereof serves to set the machine to register the particular fare which has been received. The rotary 60 movement of the actuator shaft and the actuator is accomplished by means of a transversely reciprocating plate 209 slidably mounted on a bracket 210 and having at its rear edge a depending rock 211 meshing 65 with a pinion 212 rigidly secured to the inner end of a sleeve 213 telescoping the end of the actuating shaft and journaled in the end member 200. The outer end of this sleeve has rigidly secured thereto a plate 214 having mounted thereon spring-pressed pawls 215 adapted to engage a toothed wheel 216 rigidly secured to the outer end of the shaft 204. Rigidly secured to the inner end of the actuating member 9 is a block 65 217 having a series of projections 218, any one of which is adapted, when in its proper position, to enter a gap 219 formed in the plate 209 upon the forward movement of the actuating member. The projections upon the actuating member being held against lateral movement it will be obvious that the longitudinal movement thereof will impart a transverse movement to the plate 209 and that this transverse movement will be transmitted to the actuating shaft 204 and actuator 205, thereby providing the necessary movement to the member to cause the counter to register the fare which has been received. The remainder of the register 70 bears no direct relation to the present invention and it is not necessary to describe the same. In order to connect the actuating member with the operating mechanism of my invention I have provided the same with an elongated portion or shaft 10 and have provided selector mechanism, under the control of the conductor, for actuating this shaft to set the register to register the desired fare and have provided other mechanism independent of the selector mechanism for actuating the fare register to register the fare. For the purpose of illustrating the invention I have shown, in the drawings, one form of selector mechanism, 75 in which I have provided the shaft 10 with a pinion 11 which is so mounted on the shaft as to cause the shaft to rotate therewith, but to allow the shaft free longitudinal movement relatively thereto. This is ref. 130

erably accomplished by mounting the shaft in suitable brackets or bearings 12 extending transversely to the shaft and supported by side members 13 of the supporting frame 14. The pinion 11 is loosely mounted on the shaft between the brackets 12 and has secured thereto a spline or key which is slidably mounted in an elongated groove or key-way in the shaft 10. Thus it will be seen that, when the pinion is rotated, the shaft will be caused to move therewith, but that the shaft may be moved longitudinally, relatively to the pinion 11, the pinion being held against longitudinal movement by the brackets 12. This pinion meshes with a rack 17 supported by a carriage 18, which extends transversely to the shaft 10 and is mounted upon suitable guides carried by the side members 13 of the frame 14 and here shown as shafts or rods 19. This carriage is provided with a plurality of movable stops, one for each fare which the fare register is adapted to register, adapted to be moved from their normal positions and caused to project beyond that portion of the carriage upon which they are supported. These stops are here shown as vertically movable pins 20 mounted in the horizontal portion 21 of the carriage and adapted to be projected above the carriage, but held normally in their lower or retracted position by means of springs 22 coiled about the respective pins 20 and bearing at their opposite ends against the horizontal portion 21 of the carriage and collars 23 secured to the lower ends of the pins. Any suitable means may be employed for selecting and elevating the desired stop or pin 20. In the present instance I have employed electro-magnets for this purpose and have shown each of the pins 20 as provided with a lever 24 pivotally mounted between its ends on pivot lugs 25 supported on the carriage 18 and having one end loosely connected to the pin, preferably by providing the lever with a slot or elongated recess 26 adapted to engage a projection 27 secured to the stop or pin 20. The opposite end of the lever 24 is loosely connected to the armature of an electro-magnet. In the present instance this end of the lever 24 is provided with a slot or elongated recess 28 adapted to receive a pin 29 carried by an extension or lug 30 secured to the core 31 of a solenoid 32. Each solenoid is provided with a separate electrical circuit 33, each of which circuits is provided with a circuit breaker and closer, as hereinafter described.

An actuating member of any suitable character is movably mounted near the carriage 18 and is adapted to engage one of the stops or pins 20 when it is in its projected position and actuate the same to move the carriage 18 a distance sufficient to impart the necessary amount of rotation

to the shaft 10 to set the fare register to register the fare corresponding to the particular pin which has been projected. In the present instance I have shown this actuating member as a cam plate 34 extending transversely to the carriage 18 and provided with a cam opening 35 substantially triangular in shape and having its base 36 extending transversely to the plate and located at a point on one side of the several stops 20 and having its apex located substantially midway between the opposite sides of the cam plate, on the opposite side of the several stops 20, at a distance therefrom, and provided with a recess 37 of a size sufficient to admit the entrance of one of the pins 20. Any suitable means may be provided for supporting and actuating this cam plate 34, but I have here shown the forward end thereof, that is, the end adjacent to the apex of the triangular opening therein as provided with a pair of pivot lugs 38 having pivotally connected thereto the upper end of an arm or link 39, the lower end of which is mounted on a shaft 40 having its ends mounted in the side members 13 of the frame 14. The opposite end of the cam plate 34 is here shown as provided with three pairs of pivot lugs 41, to each of which is pivotally connected the upper end of an arm or link 42, the lower ends of which are mounted on a shaft 43 supported at its opposite ends in the side members 13 of the frame 14. A suitable electro-magnet, here shown as a solenoid 44, has its armature connected to one of the links 42. In the present instance, the core 45 of the solenoid is shown as provided with pivot lugs 46, by means of which it is pivotally connected to the central link or arm 42. When the solenoid 44 is energized, the cam plate 34 will be moved longitudinally of the shaft 10 and one of the inclined walls of the aperture 35 will engage the pin 20 which has been elevated by the solenoid 32, and, as the cam plate 34 continues its movement, this pin, the carriage to which it is secured and the rack mounted on said carriage will be moved transversely to the shaft 10 and will rotate the same. When the solenoid 44 has been deenergized, the cam plate 34 is moved to its normal or idle position by means of a suitable spring 46, which is here shown as coiled about the shaft 40, and having one end connected to a stop 46^b carried by the link or arm 39 supporting the adjacent end of the cam plate 34. The solenoid 44 is mounted in a circuit 47 which is independent of the circuits controlling the several solenoids 32 and is provided with a circuit breaker and closer under the control of the conductor.

As stated, any suitable circuit breaker and closer may be employed for controlling the several circuits 33 and the circuit 47,

but I prefer to provide a circuit breaker and closer so constructed that a single operation will serve to successively close the desired one of the circuits 33 and the circuit 47, thus successively operating the solenoids 32 and 44 to actuate the selector mechanism. In the drawings I have shown one form of circuit breaker and closer for accomplishing this result. As here shown, this circuit breaker and closer comprises a casing 48 which may be mounted upon the partition 8 at the rear end of the car or in any other suitable position within reach of the conductor when he is in his place back of the railing 5. Mounted in the casing 48 and extending longitudinally thereof is a frame or partition 49, preferably of insulating material and having mounted on each side thereof a series of pairs of contact fingers 50 and 51. Each series contains the same number of pairs of contact fingers and the corresponding pairs of each series are arranged substantially opposite one to another on the partition or frame 49, which frame is provided with openings 52 substantially in alignment with the corresponding contact fingers on the opposite sides of the partition. Each pair of contact fingers 50 is connected to one of the circuits 33, while all of the contact fingers 51 are connected to the circuit 47. A series of push-rods 53 are mounted in the casing 48 and are arranged in substantial alignment. The number of these rods is equal to the number of pairs of contact fingers in each series, there being one push-rod for each fare which the fare register is adapted to register and each rod being provided on its outer end with a button or head 54 bearing the name of the particular fare which it is adapted to set the machine to register. Each of the push-rods 53 is provided with two contact points, here shown as pins 55 and 56 formed of conducting material and insulated one from the other. These collars or contact points are so arranged on the push-rods 53 that the contact 55 will engage the contact fingers 50 before the contact 56 will engage the contact fingers 51. Thus, when the push-rod 53 is pushed inwardly, the contact 55 will engage the contact fingers 50 and close the circuit 33 through the magnet 32 which is connected with the pin 20 corresponding to the push-rod which has been operated and this pin 20 will be moved into its elevated position. As the push-rod 53 continues its movement inwardly, the contact 56 will engage the contact fingers 51 and close the circuit 47 through the solenoid 44, actuating the same to move the cam plate 34, thereby actuating the pin 20 and the carriage 18 to rotate the shaft 10 and set the machine to register the fare indicated on the button 54 of the push-rod which has been operated. It will be understood that the contact fingers 50 are of such a length that the contact 55 will remain in engagement therewith, maintaining the circuit 33 closed, until the contact 50 has engaged the contact fingers 51, thus retaining the pin 20 in its elevated position until the cam plate has been actuated. I have also provided means for preventing more than one of the push-buttons 54 from being actuated at the same time. To this end, I have provided the casing 48 with a projection 58, in which the push-rods 53 are mounted and which is provided with a horizontal slot or guideway 59, the push-rods 53 having their upper portions, which extend into this slot, cut away, as shown at 60, thereby forming a continuous slot. Mounted in this slot are a plurality of disks 61, the combined width of which is less than the length of the slot 59, the difference between the combined width of the several disks 61 and the length of the slot 59 being substantially equal to the greatest diameter of one of the push-rods 53. Each push-rod has its upper portion, which lies adjacent to the cut-away portion 60, pointed, as shown at 62. Thus, it will be seen that, when one of the push-rods 53 is moved inwardly, the pointed upper portion thereof will engage the periphery of the adjacent disk 61 and will move between that disk and its neighboring disk, thereby forcing the two disks apart and entering between them. If, with one of the push-rods in its innermost position between the disks, as described, an effort is made to push in one of the other push-rods, the point 62 thereof will engage the periphery of the adjacent disk, but, inasmuch as that disk is held against movement by the push-rod which has already been pushed in, the last-mentioned push-rod is locked against movement. Each of the push-rods 53 is provided with a spring 63 mounted in the extension 58 to the housing 48 and bearing at one end against the wall of the housing 48 and at the other end against a projection 64 carried by the push-rod. This spring tends to move the push-rod outwardly as soon as the pressure thereon has been released and break both the circuit 33 and the circuit 47. In the diagrammatic figure I have shown the circuits 33 and 47 as connected to a battery 65, but it will be understood that these circuits may be energized from any suitable source of electric power, and, in actual practice, it will probably be found advisable to connect the same to the power circuits by means of which the car is propelled. In Fig. 1 of the drawings I have shown a car as equipped with two circuit breakers and closers, one secured to the partition separating the car from the platform and the other arranged on the floor of the platform and preferably carried by a support, as

shown at 48^a, this support being hinged to or pivotally mounted on the car at 48^b so that, when not in use, it can be turned up against the partition 8 and will be out of the way of persons on the platform. Each of the circuit breakers and closers is connected to the several solenoids 32 and to the solenoid 44 by separate circuits and either may be operated to set the fare register and 10 the fare indicator.

While I have here shown the car as equipped with two circuit breakers and closers it will be apparent that any suitable number may be employed, and that these 15 may be arranged in any suitable manner and that the present arrangement is for the purpose of illustration only. Also it will be apparent that, while I have here shown each of the circuit breakers and closers as 20 connected with all of the solenoids, one of the circuit breakers and closers might be connected to a part of the circuits to control the fare register and the indicator to set the same to register and indicate certain fares 25 and that the other of the circuit breakers and closers might be connected with the remainder of the circuits to control the fare register and indicator to register and indicate the remainder of the fares which the 30 apparatus is adapted to register and indicate.

From the foregoing description it will be seen that the actuating member 9 of the part to be operated, which, in the present instance, may be either the fare register or the fare indicator, is operatively connected by means of the shaft 10 and pinion 11 with a movable member or carriage 18, which member is provided with suitable means for 40 operating the same. In the present instance this operating means is shown as an operating member or cam plate 34. One of these members, in the present instance, the movable member 18, is provided with a series 45 of movable stops, any one of which may be moved into the path of the other operating member, this part being, in the present instance, the inclined wall of the opening 33 in the cam plate 34. It will also be seen 50 that I have provided means under the control of the conductor for operating the movable stops, which means is so controlled that not more than one of the stops can be moved 55 into its operative position to engage the part carried by the operating member, at one time.

Suitable means are provided for moving the shaft 10 longitudinally to actuate the fare registering mechanism to register the fare which the fare register has been set to 60 register in the manner above described. This mechanism may be actuated in any suitable manner, but I have, in the present instance, shown the same of a construction 65 adapted to be operated by the passenger as

he enters the car, and, to this end, I have provided the shaft of the turnstile 6 with an upwardly extending portion 66 supported at its upper end in a bearing bracket 67 and provided with a bevel gear 68 adapted 70 to mesh with a bevel pinion 69 carried by a horizontal shaft 70 which extends longitudinally of the car through the partition 8 and has its inner end supported in a suitable bearing bracket 71 which extends inwardly 75 from the partition 8. This shaft is provided, at a point substantially in alignment with the shaft 10, with a crank arm 72 which is connected to one end of a connecting rod 73, the opposite end of which is 80 connected with the shaft 10. In order that the shaft 10 may move relatively to the connecting rod 73 I prefer to make the connection between the two members by means of a turn buckle 74, one end of which is 85 pivotally connected to the adjacent end of the connecting rod 73 and the opposite end of which is provided with a longitudinal bearing in which is mounted the shaft 10, this shaft being held against longitudinal 90 movement relatively to the turn buckle by means of a collar 75 which is rigidly secured to the shaft 10 in a recess 76 at the rear end of the longitudinal bearing. Thus, when the shaft 70 is rotated by the action 95 of the turnstile 6, the shaft 10 will be moved longitudinally and the fare register operated to register the fare. The turnstile is here shown as of the ordinary type which is provided with four arms. Consequently, 100 the gearing connecting the shaft 66 and the horizontal shaft 70 is of such a ratio that one quarter of a revolution of the shaft 66 of the turnstile will rotate the shaft 70 through a complete rotation. In 105 order that the shaft 66 may make a complete quarter rotation at each operation of the turnstile, I have provided the same, preferably at a point above the bevel gear 68, with a disk or plate 77 which is rigidly 110 secured thereto and is provided at equal distances about its periphery with four V-shaped notches 78 adapted to receive the tapered end of a spring-pressed pin 80 115 which is slidably mounted in a bracket 81 carried by the upper portion of the car. Thus, when the turnstile is operated to rotate the shaft 66 but is stopped before the shaft has moved through a complete quarter of a revolution, the tapered end of the pin 120 80 will enter the adjacent notch 78 and the pressure of the spring-pressed pin against the inclined wall of the notch will cause the plate and the shaft, to which it is secured, to rotate until the point of the pin 80 engages the apex of the notch. This device 125 not only serves to cause the shaft 66 to make a complete quarter of a revolution at each operation thereof but it also, the same, against insertion until sufficient force is 130

applied thereto to overcome the pressure of the spring-preserved pin against the inclined walls of the V-shaped notch.

The mechanism for operating the fare register to register a fare is provided with suitable means for locking the same against movement until the selector mechanism has been actuated to set the fare register. This locking means is here shown as consisting of a finger 82 rigidly mounted on the shaft 70 and having a straight face on one side adapted to engage the end of an arm 83 which is pivotally mounted on the shaft 40 and which serves, when in engagement with the finger 82, to hold the shaft 70 against forward movement, thus effectually preventing the longitudinal movement of the shaft 10. In order that this locking mechanism may be released when the selector mechanism is actuated, the link or arm 39, which supports the forward end of the cam plate 31, is provided at its lower end with a toe 84 adapted to engage beneath a pin 85 carried by the arm 83 and, when the cam plate 31 is moved rearwardly, to elevate the arm 83 out of the path of the finger 82, leaving the shaft 70 free to rotate. The end of the arm 83 is provided with a sliding extension 86 connected to the arm 83 by means of a spring 87 secured at one end to a lug 88 carried by the extension 86 and secured at the other end to a lug 89 carried by the forward end of the arm 83, which extends alongside of the extension 86. Thus, when the arm 83 is elevated above the upper end of the finger 82, the spring 87 will move the extension 86 rearwardly, and, if the solenoids are de-energized before the shaft is rotated, the toe 84 of the arm 83 will engage the outer end of the finger 82, thus retaining the arm 83 out of the path of that finger and permitting the shaft 70 to rotate when the turnstile is activated. When the shaft 70 is so rotated, the finger 82 will move from beneath the extension 86, and, as it completes its revolution, the straight face thereof will come into engagement with the end of the finger 83 and will force the same inwardly against the spring 87 until the finger 82 is again in engagement with the arm 83. This locking mechanism serves not only to hold the operating mechanism against movement until the selector mechanism has been actuated, but also locks the turnstile 45 against movement and prevents the passenger from entering the car until the fare has been paid and the register set to register that fare.

I have also provided a suitable fare indicator 50 to indicate the fare which has been received, which fare indicator is entirely separate from the fare register and may be located at any point that may be desirable, but it is preferable that the indicator should be so 55 located and of such a construction that it

will be visible both to the passengers within the car and to those on the platform. In the present instance I have shown an indicator which is so arranged as to indicate the amount of the fare received both to the 70 passengers in the car and to those on the platform, and, to this end, I have mounted on the panel between the entrance and exit doors, 3 and 4, and in front of the glass 90 contained in said panel, a cylindrical casing 75 91 having in the opposite sides thereof sight openings 92, one of which is visible through the glass or window 90 in the partition 8 and the other of which is visible from the rear platform. This casing may, if desired, 80 be provided above each sight opening 92 with a projection 93 bearing the legend "Fare paid." A drum 94 is rotatably mounted within the cylindrical casing 91 by means of a shaft 95 journaled in the ends of 85 said casing. This drum bears two series of fare indications, such as "Ticket", "Five cents", etc., as shown at 96. These two series of fare indications are so arranged on the opposite sides of the drum that the same fare 90 indication will always be visible at both sight openings 92. One end of the shaft 95, upon which the drum 94 is mounted, is provided with a bevel gear 97 which meshes with a bevel gear 98 carried by a vertically 95 arranged shaft 99 journaled in bearings 100 carried by the partition 8 of the car. This shaft is provided near its upper end with a pinion 101 meshing with a rack 102, which, in turn, meshes with a pinion 102^a secured 100 to the shaft 10 in a manner similar to the manner of securing the pinion 11 thereto, whereby the shaft rotates in unison with the pinion, but is capable of longitudinal movement relatively thereto. Thus, when the carriage 18 is moved transversely to the shaft 10 to rotate the same to set the fare register, the shaft 99 and the drum 94 will be rotated. The ratio of the several gears is such that the indicator drum will be rotated a distance so related to the movement of the setting mechanism as to bring into alignment with the sight openings 92 the fare indication corresponding to the fare which the fare register is set to register. In the present arrangement of the mechanism I have shown the fare indicator as actuated by the selector mechanism, by means of which the fare register is set. But it will be obvious that if it is desired to use the indicator without the register, the register can be disconnected from the selector mechanism or that the indicator can be provided with other controlling mechanism independent of that controlling the fare register.

I have also provided auxiliary means for actuating the setting mechanism and the fare indicator. This auxiliary mechanism is here shown as a bevel gear 103 mounted on the lower portion of the shaft 99 and mesh- 130

ing with a bevel gear 104 carried by a shaft 105 journaled in a supporting bracket 106 and provided with means for rotating the same, such as a handle 107. By the rotation 5 of the shaft 105, the shaft 99 will be rotated, thereby imparting movement both to the indicator drum 94 and to the rack 17, by means of which the shaft 10 is rotated. This auxiliary actuating mechanism may be used 10 either independently of the selector mechanism or may be provided in connection therewith for use in emergencies. In the present instance I have shown the device as provided with both the selector mechanism and with 15 the auxiliary actuating mechanism.

I have shown and described the invention as applied to a "pay as you enter" street car, but it will be understood that the device is readily adaptable to various types of 20 cars and will be of great utility in many positions other than that described. Further, that the invention as applied to a car of the type herein described may be modified to a great extent without departing 25 from the spirit of the invention, and, as illustrating one such modification I have, in Fig. 12 shown a "pay as you enter" car as provided with a rotary door controlling the entrance, this door being of the usual type 30 having four radial wings or panels 108 and being rotatable about a vertical axis, here shown as a shaft 109. The shaft of this rotating door may be connected to the operating mechanism in the same manner as the 35 shaft of the turnstile above described and the operation and arrangement of the several parts will be substantially the same as that above described. Further, it will be understood that, while I have shown and 40 described the invention as applied to one end of the car, it might be and probably would be applied to both ends of a street car, thus enabling the conductor to control the mechanism from the rear platform in whichever 45 direction the car might be traveling and also enabling the mechanism to be operated from both ends of the car simultaneously if such should be desirable. In order that the arms of the turnstile which is located on 50 that platform, which at the time being is the front platform, may be folded so that they will not extend in the path of the 55 passengers leaving the car by the front door, I have secured to the shaft 66 of the turnstile a casting 110 having an annular flange 111, in which are arranged a series of four notches 112 spaced equally distant about the periphery of the casting and each adapted to receive one of the arms 6 of the 60 turnstile, which arms are pivotally connected to suitable lugs 113 forming a part of the casting and located in radial alignment with the respective notches. A latch or plate 114 curved to conform to the periphery of the casting is pivotally connected 65

to the lower edge of the annular flange at one side of each of the several recesses and is adapted to be moved across the recess to retain the arm in either its uppermost or lowermost position, as the case may be. 70 Each plate 114 is provided with a recess adapted to engage a projection 115 having an enlarged head 116 and located on the opposite side of the adjacent recess.

The operation of the invention will be 75 readily understood from the description of the operation of the several parts thereof and it will be seen that I have provided an operating mechanism by means of which the fare register and the fare indicator may 80 be controlled by the conductor from his position on the rear platform; that I have provided such a mechanism in which the fare register and the fare indicator are set by the conductor to register the fare received and to indicate that fare, respectively; which is provided with mechanism adapted to extend into the path of the passenger as he enters the car and to be operated by him to register the fare; that I have 85 provided a fare indicator separate from the fare register and adapted to be employed either alone or with any type of fare register; that I have provided a fare indicator separate from the fare register which may 90 be under the control of the conductor from his position on the platform and is visible to the passengers both within the car and on the platform; that I have provided improved selector mechanism for setting the 95 register to indicate the particular fare which has been received and to set the indicator to indicate that fare; that I have provided an actuating member for controlling this selector mechanism, a single operation of which will complete the selecting and setting operation, this actuating member being here shown as a circuit breaker and closer; and also that I have provided an improved circuit breaker and closer, 100 whereby the proper circuits may be successively closed to operate the several parts of the selector mechanism in the proper order to set the machine to register the particular fare received and to set the fare indicator 105 to indicate that fare.

I wish it to be understood that I do not desire to be limited to the details of construction shown and described, for obvious modifications will occur to a person skilled 110 in the art.

Having thus fully described my invention, what I claim as new and desire to secure by Letters Patent, is:—

1. A car, a fare register mounted therein, 115 a shaft connected to said register and having two movements, one to set said register to cause it, when operated, to register a selected fare, and the other to operate said register to cause it to register a fare, con- 120

125

ductor-operated devices to impart to said shaft one of its said movements to set the register, and passenger-actuated devices to impart to said shaft the other of its movements to operate the register to register a fare.

2. A car, a fare register mounted therein, a shaft connected to said register and having two movements, one to set said register to cause it, when operated, to register a selected fare, and the other to operate said register to cause it to register a fare, conductor-operated electrical devices to impart to said shaft one of its said movements to set the register, and passenger-actuated devices to impart to said shaft the other of its movements to operate the register to register a fare.

3. A car provided with a platform, a fare register mounted therein, a shaft connected to said register and having two movements, one to set said register to cause it, when operated, to register a selected fare, the other to operate said register to cause it to register a fare, conductor-operated devices manipulated from the platform to impart to said shaft one of its movements, to set the register, and passenger-actuated devices also manipulated from the platform to impart to said shaft the other of its movements, to operate the register to register a fare.

4. A car, a fare register mounted therein, a shaft having a rotating and reciprocating movement, the former to set the register to cause it, when actuated, to register a selected fare, and the latter to operate said register to cause it to register a fare, conductor-operated electrical devices including magnets and their circuits, operating first to set devices corresponding with a particular fare and second to rotate said shaft, whereby the conductor sets the register for a particular fare, and passenger-operated devices to reciprocate said shaft to register a fare.

5. A car, a fare register mounted therein, a shaft having a rotating and reciprocating movement, the former to set the register to cause it, when actuated, to register a selected fare and the latter to operate said register to cause it to register a fare, conductor-operated electrical devices, manipulated from the platform, including magnets and their circuits, operating first to set devices corresponding with a particular fare and second to rotate said shaft, whereby the conductor sets the register for a particular fare, and passenger-operated devices also manipulated from said platform, to reciprocate said shaft to register a fare.

6. In a mechanism of the character described, a fare register, a shaft connected to said fare register, and capable of two movements, means for imparting one movement to said shaft to set said register, other means for imparting another movement to

said shaft to operate said register to register a fare, and means for locking the last-mentioned means against movement until the first-mentioned means has been actuated.

7. In a mechanism of the character described, a fare register, a selector mechanism connected to said register for setting the same, and a mechanism connected to said register for operating the same to register a fare, of means for locking said operating mechanism against movement until said selector mechanism has been actuated.

8. In a mechanism of the character described, the combination, with a part to be actuated, and an actuating member therefor, of a member movable relatively to said actuating member and adapted to impart movement thereto, an operating member movably supported near said movable member and means movable relatively to both said movable member and said operating member for operatively connecting said members one to the other.

9. In a mechanism of the character described, the combination, with a part to be actuated, and an actuating member therefor, of a movable member connected to said actuating member and adapted to actuate the same, an operating member movably supported near said movable member, and a stop carried by one of said members, movable relatively thereto and adapted to be engaged by the other of said members to actuate said movable member.

10. In a mechanism of the character described, the combination, with a part to be actuated, and an actuating member therefor, of a movable member operatively connected to said actuating member, an operating member movably supported near said movable member, and a stop movably mounted on said movable member and adapted to be engaged by said operating member to actuate said movable member.

11. In a mechanism of the character described, the combination, with a part to be actuated, and an actuating member therefor, of a movable member operatively connected to said actuating member, an operating member movably supported near said movable member, and a plurality of movable stops carried by one of said members and adapted to be moved into the path of a part carried by the other of said members.

12. In a mechanism of the character described, the combination, with a part to be actuated, and an actuating member therefor, of a movable member operatively connected to said actuating member, an operating member movably supported near said movable member, and a plurality of stops carried by said movable member and adapted to be moved into the path of a part carried by said operating member.

13. In a mechanism of the character de-

scribed, the combination, with a part to be actuated, and an actuating member therefor, of a movable member operatively connected to said actuating member, an operating member movably supported near said movable member, a plurality of stops carried by said movable member and adapted to be moved into the path of a part carried by said operating member, and means for locking all but one of said stops against movement.

14. In a mechanism of the character described, the combination, with a part to be actuated, and an actuating member therefor, of a movable member connected to said actuating member and adapted to operate the same, an operating member movably mounted near said movable member and having a part provided with an inclined wall, and a stop carried by said movable member and adapted to be moved into the path of that part of said operating member having the inclined wall.

15. In a mechanism of the character described, the combination, with a part to be actuated, and an actuating member therefor, of a movable member operatively connected to said actuating member, an operating member movably mounted near said movable member and having a part provided with an inclined wall, a plurality of stops carried by said movable member, and means for moving any one of said stops into the path of that part of said operating member having the inclined wall.

16. In a mechanism of the character described, the combination, with a part to be actuated, and an actuating member therefor, of a movable member operatively connected to said actuating member, an operating member movably mounted near said movable member and having a part provided with an inclined wall, a plurality of stops carried by said movable members, means for moving any one of said stops into the path of that part of said operating member having the inclined wall, and means for locking the remaining stops against movement when one of said stops has been moved into its operative position.

17. In a mechanism of the character described, the combination, with a part to be actuated, and an actuating member therefor, of a movable member operatively connected to said actuating member, a cam plate movably mounted near said movable member, a plurality of stops carried by said movable member, and means for moving one of said stops into position to be engaged by said cam plate.

18. In a mechanism of the character described, the combination, with a part to be actuated, and an actuating member therefor, of a movable member operatively connected to said actuating member, a cam plate mov-

able transversely to the direction of movement of said movable member, a plurality of stops carried by said movable member and arranged longitudinally to the direction of movement thereof, and means for moving one of said stops into a position to be engaged by said cam plate.

19. In a mechanism of the character described, the combination, with a part to be actuated, and an actuating member therefor, of a movable member operatively connected to said actuating member, a cam plate movable transversely to the direction of movement of said movable member and provided with an opening having one of its walls inclined to the direction of movement of said plate, a plurality of stops carried by said movable member, and means for moving one of said stops into a position to be engaged by the inclined wall of the opening in said cam plate.

20. In a mechanism of the character described, the combination, with a part to be actuated, and an actuating member therefor, of a movable member operatively connected to said actuating member, a cam plate movable transversely to the direction of movement of said movable member and provided with an opening having two of its walls inclined to the direction of movement of said cam plate, a plurality of stops carried by said movable member, and means for moving one of said stops into a position to be engaged by one of the inclined walls of the opening in said cam plate.

21. In a mechanism of the character described, the combination, with a part to be actuated, and an actuating member therefor, of a movable carriage operatively connected to said actuating member, a cam plate movably supported above said carriage, a plurality of vertically arranged pins mounted on said carriage, and means for moving one of said pins into position to be engaged by said cam plate.

22. In a mechanism of the character described, the combination, with a part to be actuated, and an actuating member therefor, of a movable carriage operatively connected to said actuating member, a cam plate movably supported near said carriage, a plurality of stops movably mounted on said carriage, a corresponding plurality of electro-magnets supported on said carriage, means for operatively connecting the armatures of said electro-magnets to said stops, respectively, whereby, when one of said electro-magnets is energized, the corresponding stop will be moved into the path of said cam plate.

23. In a mechanism of the character described, the combination, with a part to be actuated, and an actuating member therefor, of a movable carriage operatively connected to said actuating member, a cam plate mov-

ably supported near said carriage, a plurality of stops movably mounted on said carriage, a corresponding plurality of sole-noids supported on said carriage, a plurality of levers supported on said carriage and connected at one end to the cores of said solenoids, respectively, and at the other end to said stops, respectively, whereby, when one of said solenoids is energized, the 5 corresponding stop will be moved into the path of said cam plate.

24. In a mechanism of the character described, the combination with a part to be actuated, and an actuating member therefor, 15 of a movable carriage operatively connected to said actuating member, a cam plate supported near said carriage, a plurality of stops mounted on said carriage and adapted to be moved into a position to be engaged 20 by said cam plate, and means for successively actuating one of said stops to move the same into the path of said cam plate and actuating said cam plate to engage said stop and move said carriage.

25. In a mechanism of the character described, the combination, with a part to be actuated, and an actuating member therefor, 25 of a movable carriage operatively connected to said actuating member, a cam plate mov- 30 ably supported near said carriage, an electro-magnet operatively connected to said cam plate, a plurality of stops mounted on said carriage and adapted to be moved into a position to be engaged by said cam plate, 35 a corresponding plurality of electro-magnets mounted on said carriage, each of said electro-magnets being operatively connected to one of said stops, and means for successively operating one of the magnets on said 40 carriage to move one of the stops into its operative position and the magnet connected to said cam plate to actuate the same.

26. In a mechanism of the character described, the combination, with a part to be actuated, and an actuating member therefor, 45 of a shaft connected to said actuating member, a pinion mounted on said shaft and adapted to rotate in unison therewith, a carriage movable transversely to said 50 shaft, a rack mounted on said carriage and adapted to engage said pinion, a cam plate movable transversely to said carriage, a plurality of stops mounted on said carriage, means for moving one of said stops into position to be engaged by said cam plate, and 55 means for actuating said cam plate to engage said stop and move said carriage.

27. In a mechanism of the character described, the combination, with a part to be actuated, an actuating member therefor, 60 a longitudinally movable shaft connected to said actuating member, a movable member operatively connected to said shaft and adapted to rotate the same, a cam plate mov- 65 ably mounted near said movable member,

and a stop carried by said movable member and adapted to be moved into position to be engaged by said cam plate, of a shaft operatively connected to said longitudinally movable shaft, means for rotating said last-mentioned shaft, and means controlled by the movement of said cam plate for locking said shaft against rotation until said cam plate has been actuated. 70

28. In a mechanism of the character described, the combination, with a part to be actuated, and an actuating member therefor, a longitudinally movable shaft connected to said actuating member, a movable member operatively connected to said shaft and 75 adapted to rotate the same, a cam plate movably mounted near said movable member, and a stop carried by said movable member and adapted to be moved into position to be engaged by said cam plate, of a shaft operatively connected to said longitudinally movable shaft, means for rotating said last-mentioned shaft, a stop carried by said last-mentioned shaft, an arm pivotally supported 80 near said cam plate and adapted to extend into the path of said stop, and means operatively connected to said cam plate for moving said arm out of the path of said stop when said cam plate is actuated. 85

29. In a mechanism of the character described, the combination, with a part to be actuated, an actuating member therefor, a longitudinally movable shaft connected to said actuating member, selector mechanism comprising a frame, a carriage movably mounted thereon and operatively connected to said shaft to rotate the same, a cam plate, links movably connecting said cam plate to said frame, means for actuating said cam plate, a stop mounted on said carriage and 100 adapted to be moved into position to be engaged by said cam plate, of a shaft operatively connected to said longitudinally movable shaft, means for rotating said last-mentioned shaft, a stop carried by said last-mentioned shaft, an arm pivotally mounted on 105 said frame, and a toe connected to one of said links and adapted to engage a part carried by said arm, whereby, when said cam plate is actuated, said arm will be moved 110 out of the path of the stop carried by said last-mentioned shaft. 115

30. In a mechanism of the character described, the combination, with a part to be actuated, and an actuating member therefor, 120 a longitudinally movable shaft connected to said actuating member, a movable member operatively connected to said shaft and adapted to rotate the same, a cam plate movably mounted near said movable member, 125 and a stop carried by said movable member and adapted to be moved into position to be engaged by said cam plate, of a shaft operatively connected to said longitudinally movable shaft, means for rotating said last- 130

mentioned shaft, a stop carried by said last-mentioned shaft, an arm pivotally supported near said cam plate and adapted to extend into the path of said stop, means operatively connected to said cam plate for moving said arm out of the path of said stop when said cam plate is actuated, an extension secured to the end of said arm, and means for moving said extension outwardly when the end 10 of said arm has been moved out of engagement with said stop.

31. In a mechanism of the character described, the combination, with a part to be actuated, an actuating member therefor, a 15 movable member operatively connected to said actuating member, an operating member movably supported near said movable member, an electro-magnet for actuating said operating member, a plurality of stops 20 mounted on said movable member, a corresponding plurality of electro-magnets mounted on said movable member and operatively connected to the respective stops, and independent circuits for each of said magnets, 25 of means for successively closing the circuit through one of said last-mentioned magnets and the circuit through said first-mentioned magnet.

32. In a mechanism of the character described, the combination, with a part to be actuated, an actuating member therefor, a 30 movable member operatively connected to said actuating member, an operating member movably supported near said movable member, an electro-magnet for actuating said operating member, a plurality of stops mounted on said movable member, a corresponding plurality of electro-magnets mounted on said movable member and operatively connected 35 to the respective stops, and independent circuits for each of said magnets, of a circuit breaker and closer comprising contact fingers connected to each of said circuits, and a push-rod having two contacts thereon adapted to successively engage the contact fingers of the circuit of one of said last-mentioned magnets and the contact fingers of the circuit of said first-mentioned magnet.

33. In a mechanism of the character described, the combination, with a part to be actuated, an actuating member therefor, a 50 movable member operatively connected to said actuating member, an operating member movably supported near said movable member, an electro-magnet for actuating said operating member, a plurality of stops mounted on said movable member, a corresponding plurality of electro-magnets mounted on said movable member and operatively connected 55 to the respective stops, and independent circuits for each of said magnets, of a circuit breaker and closer comprising contact fingers in each of the circuits of said last-mentioned magnets, a plurality of 60 contact fingers in the circuit of said first-

mentioned magnet arranged adjacent to the contact fingers of the several circuits of the last-mentioned magnets, a plurality of push-rods, each of said push rods having two contact surfaces so spaced thereon that 70 the movement of said rods will cause said contact surfaces to successively engage the contact finger in the circuit of one of said last-mentioned magnets and one pair of contact fingers in the circuit of said first-men- 75 tioned magnet.

34. In a mechanism of the character described, the combination, with a part to be actuated, an actuating member therefor, a 80 movable member operatively connected to said actuating member, an operating member movably supported near said movable member, an electro-magnet for actuating said operating member, a plurality of stops mounted on said movable member, a corresponding 85 plurality of electro-magnets mounted on said movable member and operatively connected to the respective stops, and independent circuits for each of said magnets, of a plurality of push-rods adapted to close 90 the circuit through one of said last-mentioned magnets and through said first-mentioned magnet, and means for preventing the operation of more than one of said push-rods at one time.

35. In a mechanism of the character described, the combination, with a part to be actuated, an actuating member therefor, a 95 movable member operatively connected to said actuating member, an operating member movably supported near said movable member, an electro-magnet for actuating said operating member, a plurality of stops mounted on said movable member, a corresponding 100 plurality of electro-magnets mounted on said movable member and operatively connected to the respective stops, and independent circuits for each of said magnets, of a plurality of push-rods adapted to close 105 the circuit through one of said last-mentioned magnets and through said first-mentioned magnet, and locking mechanism actuated by the operation of one of said push-rods to lock the remainder of said 110 push-rods against movement.

36. In a mechanism of the character described, the combination, with a part to be actuated, an actuating member therefor, a 115 movable member operatively connected to said actuating member, an operating member movably supported near said movable member, an electro-magnet for actuating said operating member, a plurality of stops mounted on said movable member, a corresponding 120 plurality of electro-magnets mounted on said movable member and operatively connected to the respective stops, and independent circuits for each of said magnets, of a circuit breaker and closer comprising a casing, a plurality of push-rods 125 mounted on said movable member and operatively connected to the respective stops, and independent circuits for each of said magnets, of a circuit breaker and closer comprising a casing, a plurality of push-rods 130

- slidably mounted in said casing and each adapted to successively close the circuits through one of said last-mentioned magnets and through said first-mentioned magnet, a 5 guideway in said casing adjacent to said push-rods, a plurality of disks arranged in said guideway, the combined width of said disks being less than the length of said guideway, each of said push-rods having a 10 portion of one side thereof cut away to receive said disks, and a part carried by said push-rods at one end of said cut-away portion adapted to engage the adjacent disk and move the same out of the path of said 15 push-rod.
37. In a mechanism of the character described, the combination, with a fare register having an actuating member, a rotatable shaft connected to said actuating member, 20 selector mechanism connected with said shaft and having means to control the rotation thereof, and means for actuating said mechanism, of a fare indicator operatively connected with said shaft independently of 25 said fare register.
38. In a mechanism of the character described, the combination, with a fare register, an actuating member therefor, a rotatable shaft connected to said actuating 30 member, and means for rotating said shaft, of a fare indicator, a shaft operatively connected to said fare indicator, a pinion secured to said shaft, a rack adapted to mesh at one end with said pinion, and a pinion 35 mounted on said first-mentioned shaft and adapted to mesh with the other end of said rack.
39. In a mechanism of the character described, the combination, with a fare register, an actuating member therefor, a rotatable shaft connected to said actuating member, selector mechanism adapted to rotate said shaft, of a fare indicator operatively connected to said rotary shaft, and 45 means independent of said selector mechanism for actuating said fare indicator and said rotary shaft.
40. In a mechanism of the character described, the combination, with a fare register, an actuating member therefor, a rotatable shaft connected to said actuating member, and selector mechanism for rotating said shaft, of a fare indicator, a shaft operatively connected to said fare indicator, 50 means for rotating said last-mentioned shaft from the first-mentioned shaft, and means for rotating said last-mentioned shaft independently of said selector mechanism.
41. In a mechanism of the character described, the combination, with a part to be actuated, an actuating member operatively connected thereto, selector mechanism operatively connected to said actuating member, and electro-magnets for controlling said selector mechanism, of a plurality of circuit 55 breakers and closers connected to each of said electro-magnets, said circuit breakers and closers being located in different positions.
42. In a mechanism of the character described, the combination, with a car, a fare register mounted thereon, a fare indicator separate from said fare register, selector mechanism operatively connected to said fare register and said fare indicator, and 60 electro-magnets for actuating said selector mechanism, of a plurality of circuit breakers and closers connected to each of said magnets, one of said circuit breakers and closers being supported on the walls of said car and another of said circuit breakers and closers being supported from the floor of said car. 70
43. In a mechanism of the character described, the combination, with a car, a fare indicator mounted thereon, electrically controlled selector mechanism for actuating said fare indicator, and a circuit breaker and closer located on the platform of said car for controlling said selector mechanism. 75
44. In a mechanism of the character described, the combination, with a car, a fare indicator mounted thereon, electrically controlled selector mechanism for actuating said fare indicator, and a plurality of similar circuit breakers and closers located on the platform of said car for controlling said selector mechanism. 80
45. In a mechanism of the character described, the combination, with a fare register having an actuating member, of a rotatable shaft connected with said actuating member to impart movement thereto, selector mechanism connected with said shaft and having means to control the rotation of said shaft and the movement of said actuating member, and means to actuate said selector mechanism. 90
46. In a mechanism of the character described, the combination, with a fare register having an actuating member, a rotatable shaft connected to said actuating member, selector mechanism connected with said shaft and having means to control the rotation thereof, of electrical means to actuate said selector mechanism. 100
47. In a mechanism of the character described, the combination, with a fare register having an actuating member, a rotatable shaft connected with said actuating member, selector mechanism connected with said shaft and having means to control the rotation thereof, of a fare indicator operatively connected to said shaft independently of said fare register, and electrical means to actuate said selector. 110
48. In a mechanism of the character described, the combination, with a plurality of counters to register different classes of fares, means to actuate a selected one of said 115
- 120
- 125
- 130

- counters to cause a fare of a particular class to be registered, of electrically operated mechanism under the control of the collector to select the counter to be actuated.
- 5 49. In a mechanism of the character described, the combination, with a plurality of counters, and an actuator having both a setting movement and an operating movement, of electrically controlled selective mechanism to impart setting movement to said actuator, and means to impart operating movement to said actuator.
- 10 50. In a mechanism of the character described, the combination, with a plurality of counters, and an actuator having both a setting movement and an operating movement, of a selective mechanism to impart setting movement to said actuator, said selective mechanism comprising a plurality of electro-magnets, means to separately energize the same, and means to impart operating movement to said actuator.
- 15 51. In a mechanism of the character described, the combination, with a plurality of counters, and a single actuator having both a setting movement and an operating movement, of selective mechanism to impart setting movement to said actuator to cause it to be moved into operative relation with a selected one of said counters, said selective mechanism comprising a plurality of electro-magnets and means to separately energize the same, and means to impart operating movement to said actuator.
- 20 52. In a mechanism of the character described, a counter comprising a type wheel, a gear rigidly secured to said wheel, an actuator gear, means to move said actuator gear into a position to engage the gear of said counter, an electro-magnet operatively connected with said gear, and means to rotate said actuator gear to cause it to engage the gear of said counter and actuate said counter.
- 25 53. In a mechanism of the character described, the combination, with a counter, an actuator, and a plurality of operable parts to set and operate said actuator, of electro-magnets separately connected to two of said operable parts, and a single device to cause said magnets to be successively energized.
- 30 54. In a mechanism of the character described, the combination, with a counter, and a movable actuator, of a plurality of separably operable electro-magnets to control the position of said actuator, and a magnet to impart movement to said actuator.
- 35 55. In a mechanism of the character described, the combination, with a counter, and a movable actuator, of a plurality of separably operable electro-magnets to control the position of said actuator, and a magnet to impart movement to said actuator.
- 40 56. In a machine of the character described, the combination, with a plurality of counters, and an actuator having a setting movement and an operating movement, of a device to impart setting movement to said actuator, an electro-magnet to actuate said device, a plurality of other devices to control the setting movement of said actuator, electro-magnets to separately actuate said controlling devices, and means to impart operating movement to said actuator.
- 45 57. In a machine of the character described, the combination, with a plurality of counters, and an actuator having a setting movement and an operating movement, of a device to impart setting movement to said actuator, an electro-magnet to actuate said device, a plurality of other devices to control the setting movement of said actuator, electro-magnets to separately actuate said controlling devices, a single device to successively energize one of the last-mentioned magnets and the first-mentioned magnet, and means to impart operating movement to said actuator.
- 50 58. In a mechanism of the character described, the combination, with a counter, an actuator, setting means to move said actuator into operative relation with said counter, and operating means to cause said actuator to actuate said counter, of a series of electro-magnets to control said setting means, and a single circuit breaker and closer to successively operate said magnets.
- 55 59. The combination, with a fare register having means to set the same to register a particular fare, of a plurality of electro-magnets to control said setting means, a circuit breaker and closer which will successively energize two of said magnets, and operating means to cause said fare to be registered.
- 60 60. In combination, a turnstile, fare registering mechanism operable by said turnstile, a connection between the turnstile and registering mechanism, means locking the turnstile from movement, and means for simultaneously releasing the turnstile and adjusting the connection between the same and the registering mechanism.
- 65 61. In testimony whereof, I affix my signature in presence of two witnesses.
- 70 62. WILFRED I. OHMER.
- Witnesses:
- 75 63. EARL H. TURNER,
EDWARD L. REED.
